Attorney

UNITED STATES PATENT OFFICE.

MARTIN A. ERNTSON, OF COLLEGE PLACE, WASHINGTON.

LUBRICATOR.

1,300,941.

Specification of Letters Patent. Patented Apr. 15, 1919.

Application filed January 25, 1919. Serial No. 273,068.

To all whom it may concern:

Be it known that I, MARTIN A. ERNTSON, a citizen of the United States, residing at College Place, in the county of Walla Walla 5 and State of Washington, have invented certain new and useful Improvements in Lubricators, of which the following is a specification.

The present invention comprehends generally improvements in lubricators and more particularly relates to a pressure operable lubricator.

It is the primary aim and object of this invention to provide a device of the above 15 mentioned character designed with a secondary oil reservoir positioned between the main oil reservoir and the condensation chamber while arranged therethrough is the condensation and steam conductor pipe which 20 acts as a heating medium for the oil in the secondary chamber and thereby maintains the oil in the secondary chamber ready for immediate use.

It is an additional and equally important 25 object of this invention to provide manually operable valve means for controlling the flow or passage of oil from the secondary chamber or reservoir to the main chamber or reservoir, the secondary chamber being incidentally provided with means to permit of the filling thereof even when the lubricator is in use.

The invention also embraces the provision 35 of a device of the above mentioned character wherein a drain valve is employed and connected to the bottom of the main reservoir for draining cold water therefrom while co-acting therewith is a removable plug in the condensation chamber which permits of the 40 filling of the condensation chamber with hot water which is conducted to the main chamber or reservoir subsequent to the closing of the drain valve for heating the oil in the main reservoir and in consequence permitting of the quick initial use of the lubricator.

It is a more specific object of this invention to provide a device of the above mentioned character wherein the gage for the 50 main chamber or reservoir is of improved construction and is connected with the main reservoir in a manner that will permit the attendant to observe the last drop of oil in the main chamber or reservoir; and to also 55 provide improved means for guiding the

minute quantity of oil upwardly through the pipe.

Among the other aims and objects of this invention may be recited the provision of a device of the above mentioned character 60 wherein the number of parts are comparatively few, the construction simple, the cost of production low and the efficiency high.

Other objects, as well as the nature, characteristic features and scope of this invention will be more readily apparent from the following description taken in connection with the accompanying drawings and pointed out in the claims, forming a part of this specification.

The invention is clearly illustrated in the accompanying drawings, in which:—

Figure 1 is a vertical sectional view of the improved lubricator,

Fig. 2 is a fragmentary elevational detail 75 of a lower portion of the lubricator,

Fig. 3 is a transverse section taken through the connection between the main and secondary chambers or reservoirs.

Similar characters of reference are em- 80 ployed in all of the above described views, to indicate corresponding parts.

Referring now, more particularly, to the accompanying drawings there is provided a main oil chamber or reservoir 1 formed with 85 a nipple 2 at one side and has connection with a tubular support arm 3. A connection block 4 is cast from the top of the chamber 1 and serves as a support for the improved secondary oil chamber or reservoir 5. A 90 condensation chamber 6 is connected with the cap of the chamber 5 while leading to the top of the condensation chamber is a steam supply pipe 7 in which is interposed a valve casing 8, a manually operable valve 9 in 95 which serves to control the passage of steam to the chamber 6. In order that the oil in the secondary chamber 5 may be kept ready for instant use and in order that the oil may be forced from the chamber or reservoir 100 1, in a manner hereinafter to become apparent, condensation and steam conductor tubes 10 are connected with the lower portion of the condensation chamber 6 and is arranged through the chamber 5, the support 3, the connection 4 and the chamber 1 terminating short of the bottom thereof as indicated.

In order to permit of a quick and initial use of the lubricator, the bottom of the 110

chamber is depressed and the recess 11 is provided in turn with an outlet opening 12 and formed on the under surface with a valve casing 13 in which is mounted a manually operable valve 14 for coacting with the opening 12 in controlling the passage of condensation therethrough, the casing incidentally being provided with another passage 13 for co-operating with the outlet opening 12 in allowing the condensation to pass therethrough. When the condensation has been spent from the chamber or reservoir 1, hot water is poured through the filling opening 16 in the condensation reservoir 6 subsequent to the removal of the plug 17 therefrom. A manually operable plug valve 18 is mounted in the connection 4 and controls the passage of condensation water or steam through the pipes 10. It is of course to be understood that the valve 18 is left in a full open position so that the desired quantity of hot water may be placed in the chamber or reservoir 1. On the other hand, when the plug 17 is mounted in the opening and the valve 9 is in an open position, the valve 18 is adjusted so as to control the passage and condensation of steam into the chamber or reservoir 1 and in consequence regulating the flow or passage of oil from the reservoir 1 in a manner that will hereinafter be described.

In order to permit of the depositing of the oil of the chamber 5 into the chamber 1 the connection 4 is formed with a vertical bore 19 the ends of which communicate with the chambers 1 and 5 while the manually operable valve 20 serves to control the passage of oil therethrough, said valve being normally left in a closed position until such time as it is desired to use the oil in the chamber 5. In this connection it is also to be observed that the chamber 5 which is provided with a filling opening 21 is removably closed by a plug 22 and when this plug is removed the chamber may be filled with oil even when the lubricator is in operation. The plug is also provided with an air vent 23 normally closed by the manually operable plug valve 24, the valve being arranged in an open position to allow air to enter the chamber 5 at the time the valve 20 is opened thereby insuring of the passage of oil through the bore 19 into the chamber or reservoir 1, as is apparent.

In order to permit of the engaging of the oil as it is forced from the chamber or reservoir 1, a supporting bracket 25 is formed on the outer surface of the chamber 1 and is provided with a bore 26 which is arranged in communication with the chamber 1 while the upper portion of this bore is enlarged to form a seat in which is fitted the lower end of a gage glass 27 the upper end of which is arranged in communication with a hollow stem 28 the inner end of which is

in turn detachably connected with the supporting connection 4 as at 29 so as to aline with a lateral passage way 30 in the connection 4. This connection is also provided with an inverted recess 31 the dome of which has communication therewith the passage 30 while the lower edge of the recess opens into or communicates with the chamber 1 for a purpose that will presently appear. A plug 32 is mounted in the top of the stem 28 near the closed outer end thereof to facilitate the insertion and removal of the gage glass 27. By the construction and arrangement just described it will be apparent that when pressure is applied or when water formed by the condensation of the steam rises in the chamber 1 the oil will move upwardly some of it passing through the bore 26 and rising through the tube or glass 27 thence passing through the stem 28 while the rest of the oil will pass upwardly into the inverted recess 31, it being apparent of course that the attendant will be able to observe the exact amount of oil in the chamber or reservoir to the last drop.

In order that the oil will be passed from the chamber 1 a vertically disposed outlet suction tube 33 is arranged in the chamber, the upper portion being arranged within the recess 31 and in substantial alinement with the passage way 30 while the lower end is bent as at 34 and arranged in communication with a laterally extending casing 35. A sight glass 36 has its lower end fitted to and arranged in communication with the casing 35 while the opposite end is fitted in the bracket 25 as at 37. This bracket 25 is also formed with a passage way 38 the inner end of which is in communication with the sight glass while the opposite end has connection with a conducting tube 39 the outer end of which is mounted in the outlet nipple 2 as at 40, so that the proper quantity of oil will ultimately pass through the tubular support arm, being controlled thereto by the manually operable valve 41. A plug 42 is removably fitted in the bracket 25, the opening in which it is engaged being designed to facilitate the application and removal of the sight glass or tube 36 while depending from the plug is a stem 43 the lower end of which is positioned in proximity to the feeding nozzle 44 formed on the casing 35 and surrounded by the tube or sight glass 36, the wire being designed to act as a guide for the drop of oil on its way up through the water in the sight glass and thereby preventing the oil from contacting with the inner surface of the glass. A manually operable valve 45 is mounted in the casing opposite the nozzle 44 and coacts with the latter in regulating the heating of the oil. A manually operable drip valve 46 is mounted in the casing

and is designed to permit of the water contained in the sight glass 9 to be drained off whenever desired.

It is believed in view of the foregoing description that a further detailed description of the operation of the invention is entirely unnecessary. Likewise, it is believed that the advantages of the invention will be readily apparent. Still further embodiments of the invention than those herein especially defined may be resorted to as conditions or preference may dictate as may be in keeping with the hereto appended claims.

Having thus fully described the invention, what is claimed as new and desired to be secured by Letters Patent, is:—

1. In a lubricator of the character described, a main oil chamber, a secondary oil chamber in communication therewith, valve means for controlling the flow of oil from the secondary chamber to the main chamber, a condensation chamber above the secondary chamber, a conducting pipe leading from the condensation chamber and passing through the secondary chamber so as to heat the oil therein and communicating with the main chamber, and manually operable valve means for controlling the passage of condensation through the pipes.
  2. In a lubricator of the character described, a main oil chamber, a secondary oil chamber in communication therewith, valve means for controlling the flow of oil from the secondary to the main chamber, a condensation chamber above the secondary chamber, a conducting pipe leading from the condensation chamber and passing through the secondary chamber so as to heat the oil therein and communicating with the main chamber, manually operable valve means for controlling the passage of condensation through the pipes, a removable filling plug in the secondary chamber, and a valve controlled vent in said plug.
  3. In a lubricator of the character described, a main oil chamber, a secondary oil chamber in communication therewith, valve means for controlling the flow of oil from the secondary to the main chamber, a condensation chamber above the secondary chamber, a conducting pipe leading from the condensation chamber and passing through the secondary chamber and communicating with the main chamber, manually operable valve means for controlling the passage of
- condensation through the pipes, a main valve mounted in the bottom of the main oil chamber, and a removable filling plug in the condensation chamber permitting of the pouring of hot water into the condensation chamber to be ultimately used for the heating of the oil in the main chamber.
4. In a lubricator of the character described including a main oil chamber, a hollow support arm connected therewith, a condensation chamber in communication with the main oil chamber, a casing leading from the bottom of the main chamber, a pipe arranged in the main chamber having its upper end positioned at the upper part of the main chamber and its lower end in communication with the casing, a sight glass connected to and communicating with the casing, valve controlled feeding means in the casing and gage glass, a conducting pipe arranged through the main chamber communicating with the support arm and the gage glass, and a sight glass having its lower and upper ends communicating with the main chamber at a point medially of the height thereof and near the top thereof.
5. A lubricator of the character described including a main oil chamber, a connecting block integral with the top thereof, a secondary oil chamber carried with the block, the block being provided with a vertical passage way establishing communication between the chambers, valve means for controlling the flow of oil through said passage way, a condensation chamber above the secondary chamber, a conducting pipe leading from the condensation chamber and passing through the secondary chamber and communicating with the main chamber, manually operable valve means for controlling the passage of condensation through the pipes, an outlet pipe arranged in the main chamber and having its upper end positioned near the top of the main chamber, valve controlled feeding means regulating the passage of oil from the chamber and a gage glass having its lower end arranged in communication with the main chamber medially of the height thereof and having its upper end arranged in communication with the top of the main chamber.

In testimony whereof, I affix my signature hereto.

MARTIN A. ERNTSON.
